UNITED STATES PATENT OFFICE.

CHARLES W. FRAIM, OF HARRISBURG, PENNSYLVANIA.

GAME.

Application filed July 5, 1922. Serial No. 572,792.

To all whom it may concern:

Be it known that I, CHARLES W. FRAIM, a citizen of the United States of America, and resident of Harrisburg, in the county 5 of Dauphin and State of Pennsylvania, have invented certain new and useful Improvements in Games, of which the following is a specification.

This invention relates to improvements in 10 playing cards which bear, on their faces, indicia specifying official positions in the United States Government from President to Representatives. The cards have corner designations which may be accompanied by 15 numerals on some of the cards, and one of the cards carries the designation "Buck", or other selected word of like character.

The accompanying drawings illustrate 20 cards bearing indications showing the individual cards of a pack.

As shown in these drawings, one of the cards will bear the designation "President", another "Vice-President", one is marked "Speaker" and the other "Buck". There 25 are a plurality of other cards designated respectively of "Cabinet", "Senator" and "Representatives". The cards have upper and lower corner letters or abbreviations, and where there are groups of a plurality 30 of Government officers, numerals may be added.

A pack of cards may consist of sixty-one cards, or any other suitable number, the card marked "Buck" making the pack odd 35 as to numbers, and may be discarded in playing certain games, as the "joker" is in ordinary card games.

As a type of game which may be played 40 with a deck of cards as hereinbefore described, the cards may be separated into four groups of fifteen each, namely, one "President", one "Vice-President", one "Speaker", two "Cabinet", five "Senators" (numbered from 1 to 5), and five "Representatives" likewise numbered, and each of 45 these groups, in addition to the designations, may be differently colored. A game may be played by any number of persons from two to six. The cards are shuffled, 50 eight being dealt to each player. Four cards are then placed on the table, face downward. The player on the left side of the dealer starts the game, and has the privilege of laying down any of the eight cards, not to 55 exceed four in number, they being discarded face downward, and exchanging for any of

the discarded ones, which are on the table. If the player succeeds in getting a full set it counts five points in the game. There is then drawn from the deck, six more cards, 60 giving a new hand, and if the player did not succeed in getting a full set from the draw of four cards on the table, then it is the next player's turn to draw, and in like manner the game passes to the next player. 65

When the cards have all been matched so as to dispose of all the sets that can be made in each game, a call is made by the dealer to see who holds the "Buck" card, the holder of such card being charged with a loss of 70 two points, either to be deducted from the points won, or charged against the holder. The player that secures forty points wins the game.

Other games may be played, the object 75 being to hold a full set of the official designations and avoid holding the "Buck" card, as it will reduce the player's score, and the card game above described I have named "Passing the Buck".

Another game can be played with sixty cards, with from two to four players, which may be partners. The cards are dealt four at a time to each player and then four cards to the table, the cards being dealt face up. 80 The remainder of the pack is placed face downward on the table, and after the first round has been dealt, four more cards are dealt to each player, omitting the deal to the table. 85

To score points by taking in certain cards and card combinations, the counting value is as follows: Cards, greatest number of cards taken counts 4; greatest number of cards of a specific color taken counts 1; high 95 spot (#5 Senator) counts 2; low spot (#1 Senator) counts 1; and each Cabinet card counts 1.

In playing the game, each player beginning on the left of the dealer may make 100 the following plays: if the player holds a card in his hand of the same denomination as one on the table, the player may play such card and take up the two or more, as the case may be, if the cards are of the same denomination. He may also take in any other cards, the sum of which equals the denomination of the one played; thus a five will take in a five on the table, also four and one, or three and two. A combination may 110 be built of two or more cards by adding a card from the player hand to one or more

cards on the board, if the sum of such cards equals another card the player holds in his hand. A player may take from the stack being built on the next turn of the player, 5 provided no other player has taken the top card with another card of the same denomination, or has built the stack higher. Thus, if a 3 is on the board of any color, and the player holds a 5 and 2 of any color, the 10 player may build 2 on the 3 and take it on the player's next turn with a 5, provided no other player has taken it in with another 5.

After the pack is exhausted, the player taking the last combination, takes all the 15 cards remaining on the board.

Twenty-seven points wins the game. If the players each have twenty-seven points at the finish, one more deal is taken and the points counted. This game I have named 20 "Yurit".

Another similar game to the foregoing which I designate as "Construction" may be played with sixty cards, in which the cards are dealt as in "Yurit", the cards having a 25 value as follows: the greatest number of cards taken counts 5 points; if a full set is taken it counts 10 points, and for each hand taken, 1 point.

A full set in this game consists of "President", "Vice-President", "Speaker", one "Cabinet", "Senator" or "Representative" 30 in numerical order, regardless of color. A hand in this game consists of two or more cards, regardless of color.

35 In playing the game, each player begins by building from a low number to a high

one, or from a high one to a low one; thus, if the player starts to build up from one to the "President", or down from the "President" to one, and no other player takes it in, 40 the player has a full set.

If a player begins by building from one up or from "President" down, and any of the other players or the player takes the cards in at the next play, it is a hand. If any 45 of the other players do not build on another player's build, or take it in at his first turn, the player cannot take it or build on it the next time.

I claim:

1. A pack of cards comprising four suits and a single card, the cards of each suit bearing the designations "President", "Vice-President", "Speaker", two cards in each suit marked "Cabinet", five cards marked 55 "Senator" and five marked "Representative", the cards bearing the designations "Senator" and "Representative" having designating characters at the corners and numbers from 1 to 5 inclusive, making up a deck of sixty 60 cards with fifteen in each suit.

2. A deck of sixty cards made up of four suits, each suit comprising three major cards, two intermediate cards and two minor sets of five each, said minor sets being numbered 65 from 1 to 5 inclusive, the cards of each suit bearing names of official positions in the executive branch of the United States Government, for use with an additional card marked with a non-official designation.

CHARLES W. FRAIM.
